(57) **CLAIM**

The ornamental design for a motorcycle passenger footpeg, as shown and described.

DESCRIPTION

FIG. 1 is a perspective view of a motorcycle passenger footpeg.

FIG. 2 is a top plan view of the motorcycle passenger footpeg.

FIG. 3 is a bottom plan view of the motorcycle passenger footpeg.

FIG. 4 is a right side elevational view of the motorcycle passenger footpeg.

FIG. 5 is a left side elevational view of the motorcycle passenger footpeg.

FIG. 6 is a front plan view of the motorcycle passenger footpeg; and,

FIG. 7 is back plan view of the motorcycle passenger footpeg.

The broken lines immediately adjacent to the shaded areas represent the boundaries of the claimed design, while the other broken lines illustrate environment; none of the broken lines form part of the claimed design.
